CLAIM

The ornamental design for double turning trays with rotatable propeller, as shown and described.

DESCRIPTION

FIG. 1 is a front top left perspective view of double turning trays with rotatable propeller showing my new design;
 FIG. 2 is a front elevation view thereof;
 FIG. 3 is a back elevation view thereof;
 FIG. 4 is a right side elevation view thereof;
 FIG. 5 is a left side elevation view thereof;
 FIG. 6 is a top plan view thereof;
 FIG. 7 is a bottom plan view thereof; and,
 FIG. 8 is a back bottom right perspective view thereof.
